UNITED STATES PATENT OFFICE.

LOUIS C. EDGAR, OF SWISSVALE, PENNSYLVANIA.

TOY.

1,098,895.

Specification of Letters Patent.

Patented June 2, 1914.

Application filed September 8, 1913. Serial No. 788,654.

To all whom it may concern:

Be it known that I, LOUIS C. EDGAR, a citizen of the United States of America, residing at Swissvale, in the county of Allegheny and State of Pennsylvania, have invented certain new and useful Improvements in Toys, of which the following is a specification, reference being had therein to the accompanying drawing.

10 This invention relates to toys, and more particularly to that type embodying the principle of a gyroscope, wherein the center line of the axis of a revoluble member passes through the center of two portions of the toy which shall act as supporting points forming the center of the gyroscopic precessional activity of the toy.

15 The primary object of my invention is to provide a toy representing a miniature person or figure that can be made to revolve when resting on the head, a foot, an arm, or when suspended from a plurality of points not the center of gravity of the toy.

Another object of this invention is to provide a simple, durable and inexpensive toy that will afford considerable amusement to juveniles.

20 I attain the above and other objects by a mechanical construction that will be herein-
25 after specifically described and then claimed.

Reference will now be had to the drawing, wherein:—

Figure 1 is a front elevation of the toy in an upright position, Fig. 2 is a similar view 35 of the toy in an inverted position, Fig. 3 is a side elevation of the toy as resting upon an arm or one of the supporting points thereof and maintained in the position shown in two ways viz:—first, in either of 40 the directions indicated by the arrows by the energy in the revolving member or gyroscope, second, in the direction perpendicular to the plane of the paper by the shape of the arm of one of the pivot points thereof, Fig. 4 is a front elevation of a toy as suspended 45 from a flexible support, as a cord or twine and maintained in the plane shown by the energy of the revolving member or gyroscope.

50 A toy in accordance with this invention comprises a rectangular frame 1 and revolu-
55 bly mounted in said frame is a shaft 2. This shaft represents the longitudinal axis of the toy. The center line of the shaft 2 passes through one or two of the supporting

points which form the center of precession of the toy, as the top of the head or the foot, or both. Mounted upon the shaft 2, within the frame 1 is a hub 3 having a large balance wheel 4. The shaft 2 is provided with an opening 5, whereby the end of a piece of cord or twine can be temporarily connected to the shaft 2 and wound thereon, whereby when the cord or piece of twine is rapidly withdrawn, sufficient impetus is given to the shaft 2 to revolve and place the wheel 4 in motion.

Connected to one end of the frame 1 is a pair of legs, one of which is elevated or raised, and the free terminus of the other constitutes a supporting point 6 which forms the center of precession of the toy during the activity of the latter. Mounted upon the opposite end of the frame 1 is a body 7 having arms 8 and a head 9, said head serving as a supporting point, while either of the arms can be positioned whereby the body can be suspended from a cord or other flexible support, as shown in Fig. 4, or placed upon the support to revolve in a horizontal plane, as shown in Fig. 3. The arms 8 can be adjusted to various inclinations and are pivotally connected as at 8^a to the body 7. Each of the arms 8 is termed an adjustable element and can be suspended from various points thereof by a flexible support, not shown, the said points upon each of said elements forms the center of the gyroscopic precessional activity of the toy.

The balance wheel 4 is located intermediate the ends of the toy, and when the wheel gyrates with considerable speed, the toy can be placed in various positions whereby it will revolve.

From the foregoing it will be observed that the upper and lower parts of the toy can be dressed or suitably ornamented whereby the gyroscope of the toy is practically invisible, yet permitting of easy access whereby the gyroscope can be placed in action.

What I claim is:—

1. A gyroscopic toy embodying a rectangular frame, a shaft journaled in said frame, a hub mounted upon said shaft, a balance wheel carried thereby, said hub and said shaft having an opening formed therein adapted to receive the end of a cord or twine whereby the gyroscope can be placed in action, legs carried by the lower end of

- said frame with one of said legs constituting a supporting point forming the center of precession of the toy, a body carried by the upper end of said frame and constituting another supporting point forming the center of precession of the toy, and adjustable arms carried by said body and forming the center of the gyroscopic precessional activity of the toy.
- 10 2. A toy comprising a body having one or two stationary supporting points and adjustable supporting points, and a gyroscope carried by said body whereby said body can be revolved at any of said points, each of 15 said points forming the center of precession of said body.
3. A gyroscopic toy embodying a gyroscope having two stationary supporting points and a plurality of adjustable supporting points.
- 20 4. A gyroscopic toy embodying a gyroscopic element provided with an adjustable supporting point forming the center of the gyroscopic precessional activity of said element.
5. A gyroscopic toy embodying a gyroscopic element having an angularly adjustable supporting means forming the center of the gyroscopic precessional activity of said element.
- 30 6. A gyroscopic toy embodying a gyroscopic element provided with an angularly adjustable member having points thereon forming the center of the gyroscopic precessional activity of said element.
- 35 7. A gyroscopic toy comprising a gyroscopic element provided with a stationary and an adjustable supporting point, each of
- 40 said points capable of forming the center of precession of said element.
8. A gyroscopic toy embodying a gyroscopic element having a stationary and an angularly adjustable supporting point, each of said points capable of forming the center of precession of said element.
- 45 9. A toy comprising a body provided with a gyroscope, said body including an adjustable element having supporting points forming the center of the gyroscopic precessional activity of said body.
- 50 10. A toy comprising a body provided with a gyroscope, said body including an adjustable element having supporting points forming the center of the gyroscopic precessional activity of said body, said element capable of being adjusted to various angles with respect to said body.
- 55 11. A toy comprising a body carrying a gyroscope and including a stationary and an adjustable element, said elements having supporting points forming the center of the gyroscopic precessional activity of said body.
- 60 12. A toy comprising a body carrying a gyroscope and including a stationary and an adjustable element, said elements having supporting points forming the center of the gyroscopic precessional activity of said body, said adjustable element capable of being shifted to various angles with respect to said body.
- 65 In testimony whereof I affix my signature in the presence of two witnesses.
- 70 LOUIS C. EDGAR.
